UNITED STATES PATENT OFFICE.

HEINRICH SCHIPPERS, OF PATERSON, NEW JERSEY.

SWIVEL-LOOM.

SPECIFICATION forming part of Letters Patent No. 496,668, dated May 2, 1893.

Application filed April 29, 1892. Serial No. 431,151. (No model.)

To all whom it may concern:

Be it known that I, HEINRICH SCHIPPERS, a citizen of the United States, residing at Paterson, in the county of Passaic and State of New Jersey, have invented certain new and useful Improvements in Swivel-Looms, of which the following is a specification.

This invention relates to improvements in that class of looms that are known as swivel looms: and the object of my invention is to simplify the construction and thereby reduce the cost and simplify the operation of weaving with such loom.

The invention consists in various constructions and combination of parts and details, that will be fully described and set forth hereinafter and finally pointed out in the claims.

In the accompanying drawings, Figure 1 is a rear elevation of my improved swivel loom, some parts being broken out. Fig. 2 is a side view of the same, some parts being omitted. Fig. 3 is a part sectional plan-view of the same, some parts being omitted. Fig. 4 is a vertical transverse sectional view of the same, on the line 4-4, of Fig. 3, parts being omitted. Fig. 5 is an enlarged detail longitudinal sectional view of a sliding cam sleeve and the gear-wheels, and Fig. 6 is an enlarged detail-view of the gear-wheels, parts being broken out and others being in section on line 6-6 of Figs. 3 and 5.

Similar letters of reference indicate corresponding parts.

The frame A of the loom is of the usual construction and is provided with the crank-shaft A' connected by the rod A² with a lay A³ carrying the usual shuttle race and the swivel shuttle beam A⁴, which is vertically movable in relation to the lay and reed cap A¹⁰. Two vertically movable rods B are arranged and guided on the back of the lay, and are provided at their upper ends with arms B' projecting to the front and supporting the swivel shuttle beam. Said rods B are pressed upward by helical springs B² surrounding them and resting against collars B³ on the rods and against fixed stops or brackets B⁴ of the lay swords. The lower ends of the rods B are connected by links B⁵ with two bars B⁶ that are secured to a rocking shaft C in the main frame A, said bars B⁶ carrying counter-weights B' at the ends opposite those

connected with the links B⁵. The rocking shaft C is provided with an upwardly-projecting arm C', on the upper end of which a cam D can act, and which cam is fixed to a sliding sleeve D' that is splined on the cam-shaft E of the frame A, so that said sleeve D' turns with the shaft E but can slide on the same. The sleeve D' is provided with a circumferential groove D², into which the prongs of a fork F' pass, said fork projecting downward from a rocking lever F that is pivoted centrally on lugs F² of a transverse bar F³ of the machine frame. The ends of the rocking bar F are connected by wires f with the Jacquard mechanism. The driving shaft A' is provided at one end with a cog-wheel G engaging a larger cog-wheel G' provided with two opposite tappets G² that operate the picker-stick lever H. Said cog-wheel G' is mounted on the above-mentioned cam-shaft E; and the opposite end of the cam-shaft is provided with two like tappets g² that operate the other picker-stick lever h. The picker-sticks H' are connected with the picker-stick levers by straps in the usual manner. Each of the picker stick levers H and h is provided with a cam piece or shoe I, which is beveled upward toward the center, and said shoes are each formed on the front end of a bar I' pivoted at I² on the top of the corresponding picker-stick lever, and the rear ends of said bars I' are connected by two rods I³ with the opposite ends of a lever I⁴ pivoted on a bracket I⁵ on the rear end of the machine frame, and one of said rods I³ is pivotally connected at I⁶ with a lever J pivoted on a bracket J' of the frame A, and the other end of said lever J passing into a groove in a cam-sleeve that will be described hereinafter.

The swivel shuttle rack that operates the shuttles in the swivel shuttle beam in the usual manner is connected by a rod K with an arm K' on the upper end of an upright rocking-shaft K² mounted in a bracket on the lay and in a suitable bracket on the lay rock shaft, which upright shaft K² is provided at its lower end with an arm K³ that is connected by a connecting rod K⁴ with one end of a horizontally-swinging lever K⁵ pivoted to a bracket K⁶ of the machine frame. From said lever K⁵ a pin L' projects that passes into a groove of a cam-sleeve that will be described

hereinafter. On that end of the shaft E opposite the one carrying the cog-wheel G' a cog-wheel M is fixed within the frame A, the cog-wheel G' being outside of the frame. Adjacent to said cog-wheel M a cog-wheel N is fixed on one end of a sleeve O mounted loosely on the shaft E. Said cog-wheel N is provided with a squared or polygonal collar N', against which a plate N² rests which plate is secured to one end of a rod N³ mounted in suitable guides of the frame and acted upon by a helical spring N⁴ surrounding it. Said plate N² bearing against the sides of the polygonal collar N' serves to hold the wheel N and sleeve O in different positions until forcibly moved out of such positions. By the turning of the collar N' the plate N² is pushed back until the collar has made a quarter turn, when said collar is again held temporarily in position by said spring-pressed plate. On a pin P projecting from the frame A two pinions Q Q' are mounted and which are connected to rotate together, the pinion Q' engaging the cog-wheel M and the pinion Q engaging the cog-wheel N. The pinion Q is provided with teeth only on half of its circumference, as shown in Figs. 3 and 6. On the sleeve O a cam-sleeve R is mounted by means of a spline or key in such a manner that the sleeve R can slide on the sleeve O, but rotates with the latter. Said sleeve R is provided with the two annular grooves a b, and with the spiral cam-groove d. A similar cam-sleeve R' is mounted on a sleeve O' fixed on the other end of the shaft E in such a manner that the cam-sleeve R' can slide on the sleeve O', but rotates with the same. Said sleeve R' is provided with the annular grooves a' b' and with the spiral cam groove d'. The end of the lever J, pivoted on the bracket J' and previously described, enters the groove b' of the sleeve R', and the pin L' on the swinging lever K⁵ enters the groove b of the sliding sleeve R. Above the cam-sleeve R a lever S is pivoted on a standard T of the cross bar F⁸, and the outer end of said lever S is pivoted at t to the rocking lever F. Above the cam-sleeve R' a like lever S' is pivoted at T' on the bar F⁸, and at its outer end is pivoted at t' to the lever F. From the lever S two pins m and n project downward through a guide U on the under side of the bar F⁸, and in like manner two pins m' n' project downward from the pivoted lever S' through a guide U' on the under side of the bar F⁸, the pins m n being above the grooves d and a respectively of the cam-sleeve R and the pins m' n' being above the grooves d' a' respectively of the sliding sleeve R'. The rack 60 s on the swivel shuttle beam, pinion t and weighted lever r serve for shifting the swivel shuttle beam in regard to the design to be produced, and form no part of this invention.

The operation is as follows: When the loom 65 is doing plain weaving, the left-hand end of the lever F is raised (looking from the rear, as in Fig. 1) and the right-hand is lowered,

the pins n n' being in the grooves a and a' of the sliding sleeves R R' respectively. When the swivel shuttles are to be brought in operation, the swivel shuttle beam must be lowered, and then reciprocated and the ordinary picker-sticks must be stopped. At that time the lever F is brought in the position shown in Fig. 1: that is, the left-hand end is lowered 70 and the right-hand end raised. Thereby the pins n n', which previously locked the sleeves R R' in position and prevented them from sliding--are raised, and the pins m m' are lowered and pass into the cam grooves d d' 80 of the sleeves R R'. By the action of said pins on the sides of the cam grooves d d' the sleeves R R' are moved to the right. Thereby that end of the lever J in the groove b' of the sleeve R' is moved to the right and the opposite end is moved to the left, and thereby the rods I³ are moved in such a manner as to swing those ends of the bars I' with which they are connected toward each other, and the outer ends of the bars carrying the cam-shoes or heads I are swung outward, as shown in dotted lines in Fig. 3: that is, they are moved out of the path of the tappets G² and g² respectively, and thus the picker-stick levers H h are no longer actuated. At the same 95 time by the above described movement of the lever F the sleeve D' is brought in such a position that its cam D can act on the arm C' of the rocking shaft C and presses the upper end of said arm C in the direction of the arrow x, Fig. 4. Thereby those ends of the bars B⁶ connected with the vertical rods B supporting the swivel shuttle beam are pressed down and said swivel shuttle beam is thus brought in lowered position for the operation 100 of the swivel shuttles. As the pinion Q has only teeth on half its circumference, it follows that the sleeve O must remain in a position of rest during half the rotation of said pinion, and is locked in these positions of 105 rest by the spring pressed plate N² acting on the collar N'. When the machine is set for swivel weaving, the swivel shuttle beam is lowered once for each revolution of the shaft E, but does not remain in lowered position 110 during said entire revolution. The picker-sticks ordinarily make two picks for each rotation of the shaft E, but by the sliding of the cam-sleeve R' the cam-heads I on the picker-stick levers are moved out of the way once 115 during each rotation of the shaft E, and thus each picker-stick, instead of making two picks for each rotation of the shaft E makes only one pick when the loom is set for swivel weaving, and this pick is made when the swivel shuttle beam is in raised position. Likewise the swivel shuttles must make a pick at the time when the ordinary picker-sticks are at rest, and for this reason the sleeve R remains at 120 rest when the picker-sticks operate. Or in other words the sleeve R' must be shifted twice for each time that the sleeve R is shifted once, as the sleeve R' must move the cam-heads H' on the picker-sticks once out of the 125 130

way and back again for each rotation of the shaft E, and the sleeve R must cause the swivel shuttle to make only one pick. If the sleeve R were rotated as uniformly as the sleeve R', the swivel shuttles would make two picks—that is, one during the time that the cam-heads on the picker-stick levers are out of position and another when said cam-heads of the picker-stick levers are in position, and thus the two picks would interfere. This operation of alternate picks by the regular fly shuttle and the swivel shuttles is kept up as long as swivel weaving is to be performed. As soon as the weaving is to be changed to plain weaving the left-hand end of the lever F is raised, so as to bring the pins m m' out of engagement with the spiral grooves d d' of the sleeves R R', and said sleeves are locked in position as regards sliding on the shaft E by the pins n n' which pass into the grooves a a' of the sleeves R R'. At the same time the sleeve D' is shifted in such a manner as to bring the cam D out of engagement with the arm C' of the rocking shaft C.

Having thus described my invention, I claim as new and desire to secure by Letters Patent—

1. The combination, with a loom frame, of a lay and a swivel shuttle beam on the same, means for raising or lowering the swivel shuttle beam, a driving shaft in the loom frame, a cam shaft driven from the driving shaft, a cog-wheel fixed on the cam-shaft, a cog-wheel mounted loosely on the cam-shaft adjacent to the fixed cog wheel, two united pinions en-

gaging the fixed and loose cog-wheel, the pinion engaging the loose cog-wheel having teeth on half its circumference only, a sleeve connected with the loose pinion, a sliding cam-sleeve on the sleeve connected with the loose pinion, means for reciprocating the swivel rack operated from said cam-sleeve, pins for shifting the sliding cam sleeve, a lever operating said pins and wires for operating said lever from a Jacquard mechanism, substantially as set forth. 40

2. The combination, with a loom frame, a lay and a swivel shuttle beam on the same, of a driving shaft in the loom frame, a cam shaft driven from the driving shaft, a fixed cog-wheel on the cam-shaft, a loose cog-wheel on the cam-shaft adjacent to the fixed cog-wheel, two connected pinions engaging the fixed and loose cog-wheels on the cam shaft, the pinion engaging the loose cog-wheel having teeth on half its circumference only, a sleeve connected with the loose cog-wheel, a cam sleeve mounted upon the sleeve connected with the loose cog-wheel, means for automatically shifting said cam sleeve, and a swivel shuttle rack reciprocating device operated from said cam sleeve, substantially as set forth. 50

In testimony that I claim the foregoing as my invention I have signed my name in presence of two subscribing witnesses. 55
